WINDOW CONTROL DEVICE

Robert H. Butters, Atlanta, Ga.

Application March 8, 1933, Serial No. 660,011

11 Claims. (Cl. 177—314)

This invention relates to improvements in window control devices, and more particularly to a device which is adapted to hold a window in an elevated or open position and which is operative, 5 at will, to release the window and permit it to descend by gravity to its closed position.

The invention contemplates a device which is available for co-operation with a number of similar units to provide a window control system, 10 whereby the various windows of a building may be closed simultaneously when occasion demands.

One object of the invention is to provide a device of the type generally described which may be controlled either at the window with which the 15 device is associated or at a remote point, it being understood that various forms of remote controlling devices may be used.

A further object is to provide a device which is so designed that the window is closed quietly, 20 this object contemplating a device in which provision is made for regulating the speed at which the window descends from its open position to its closed position.

A still further object is to provide a device 25 which is adapted to secure the window at any one of a plurality of predetermined positions and which is operative at any one of said positions to release the window and permit it to close in the manner described.

A still further object is to provide a device which is conditioned when the window with which it is 30 associated is closed to sound an alarm in the event that the window is raised, this object contemplating a burglar alarm system in which one or more of the said devices may be connected.

A still further object is a novel arrangement of the parts of the device whereby to provide a 35 unitary construction.

The invention is illustrated in the accompanying drawings, in which:

Figure 1 is a view in elevation of a window to which a device embodying features of the invention is applied, the said device being included, together with a plurality of similar devices in a 40 combined control and burglar alarm system.

Figure 1a is a fragmentary section taken along line 1a—1a of Figure 1.

Figure 2 is an enlarged longitudinal section through one of the devices and illustrates the 45 arrangement of the parts thereof when the window is held in one of its open positions.

Figure 3 is a horizontal section taken along line 3—3 of Figure 2.

Figure 4 is a similar section taken along line 50 4—4 of Figure 2.

Figure 5 is a view similar to Figure 2 showing the arrangement of the parts of the device when the window is closed.

Figure 6 is a perspective view of the latch-piece releasing member.

Figure 7 is a similar view of the latch-piece.

The device, as illustrated, includes a housing which is provided by a box 10 and a tubular member 11. The box 10 may be made of any suitable material, a metal box being assumed in 10 the drawings, and is normally closed by a removable cover plate 10a. The tubular member carries a foot-piece 12 which is formed with a flange 13, the said flange being availed of to secure the foot-piece to the sill 14 (Figure 1) 15 of the window with which the device is associated. At its upper end the device is connected to the lower sash 15 of the window by a bracket 16, the bracket and foot-piece being secured to the sash and sill in such a manner that the control 20 box and member 11 are arranged in close proximity to a vertical frame member 17 of the window casing.

The bracket 16 is carried by a rod 18 which is mounted for movement out of and into the 25 housing as the sash is raised and lowered. The rod extends through openings 19 and 20 which are formed in the top and bottom walls, respectively, of the box 10, and is enclosed throughout its greater part of its length in the tubular member 11. In order to insulate the rod from the 30 housing, the former is preferably mounted in bushings 21 of suitable insulating material which are arranged in the openings 19 and 20. At its lower end the rod 18 carries a piston 22 which, 35 as illustrated, consists of an insulating disc 23, a sealing element 24 and a disc-like member 25, the said parts being secured against a shoulder 26, which is formed on the rod 18, by a nut 27. The rod 18 is preferably of such a length that 40 the sash 15 may, if desired, be raised to the upper limit of its range of movement. It will be apparent that the tubular member 11 provides a cylinder 11a in which the piston moves as the window is raised and lowered. An insulating disc 12a is arranged in the bottom of the cylinder 11a and is adapted to prevent the rod 18 from contacting with the foot-piece 12. The rod 18, therefore, is insulated throughout its 45 entire extent from the various parts of the device. The disc 12a is formed with an opening 12b which communicates with a passage 12c, the latter being formed in the foot-piece 12. A valve element 12d extends into the passage 12c and is adjustable to regulate the flow of air to and 50

55

from the cylinder 11a. It will be appreciated, therefore, that the speed at which the window is permitted to descend may be controlled by regulating the valve element 12d. Quiet closing of the window is thus insured. In order to facilitate opening of the window a suitable aperture may be formed in the member 11 at the upper end thereof to permit passage of air into and out of the cylinder at the upper side of the 10 piston.

Means is provided whereby the sash 15 may be held open at any one of a plurality of predetermined positions. To this end the rod 18 is formed at predetermined points with annular 15 notches 28, the said notches corresponding to the various elevated positions in which the sash may be supported. A latch-piece 29 for co-operating with the said notches is pivotally mounted in the box 10 upon a pin 30. The latter is carried by a boss 31 which is suitably formed or provided upon a vertical wall 32 of the box. In order to insulate the latch-piece 29 from the box 10 it is arranged over an insulating sleeve 33 (Figure 3) and between insulating 20 washers 34, all of the said insulating parts being carried by the pin 30. The latch-piece 29 is supported in such relation to the rod 18 that the end 35 thereof is adapted to enter a notch 28 as the latter moves to a point opposite the end 30 35. Entry of the end 35 of the latch-piece into the said notch is effected by a spring 36. The latter is connected at one end to a pin 35a which is carried by the end 35 of the latch-piece and at its opposite end to a terminal strip 37. The 35 terminal strip is secured to a side wall 38 of the box 10 by a screw 39, the said strip being insulated from the box and the screw by insulating elements 40 and 41. In the use of the device the sash 15 is raised to a point slightly 40 above the height desired and then released. As the sash is raised the latch-piece 29 is moved to the dotted line position shown in Figure 5, thereby permitting upward movement of the rod 18. When the sash is released it descends by 45 gravity until the end 35 of the latch piece enters the adjacent notch on the rod 18. It will be noted that the end 35 of the said latch-piece is preferably rounded in order to insure relative movement between the latch-piece and the rod 50 until the former enters a notch. As the end 35 enters a notch the latch-piece assumes the horizontal position which is shown in full lines in Figure 2. When the latch-piece reaches this position the opposite end 42 thereof engages a 55 shoulder 43 which is suitably formed or provided upon a member 44. The latter is pivotally mounted upon a pin 45 which is supported from the bottom wall 32 of the box. The member 44 is normally held in the position shown by a spring 60 46, the said spring being suitably secured at one end to the member 44 and bearing at its free end against a block 47. At its upper end the member 44 abuts a stop 44a which is adjustable to limit the movement of the lower end of the member in the direction of the latch-piece. 65

It will be apparent that by rocking the member 44 about the pin 45 from the position shown in Figure 2 the shoulder 43 of the said member will be moved out of the path of the end 42 of the latch-piece. Upon the release of the end 42 of the latch-piece the sash 15 moves by gravity toward its closed position. As it moves downwardly the latch-piece is moved, against the action of the spring 36, to the position shown in full lines in Figure 5, the end 42 of the latch-piece being

elevated and out of contact with the member 44. The latter is provided with an operating element 48 which extends through an opening 49 formed in the adjacent side wall of the box. Hence by depressing the said element, the member 44 is moved against the action of the spring 46 to release the latch piece and permit the window to close. The sash 15 is preferably locked in its closed position. To this end a latch 15a (Figure 1) is pivotally mounted upon the frame of the 10 window, the said latch co-operating with a stop 15b which is carried by the sash. The latch is so designed that as the sash approaches its closed position, the stop lifts and passes beneath the lower end of the latch, whereby to lock the sash in its closed position when the latch returns, by gravity, to its normal position. Locking of the window is, therefore, automatically effected as the window reaches its closed position. 15

Means is provided whereby the window may 20 be closed from a remote point. To this end an electro-magnet 50 is arranged in the control box adjacent the member 44, the said electro-magnet including the block or pole-piece 47. The electro-magnet 50 includes a conventional winding 25 which terminates at one end in a lead-wire 51 which is grounded to the box 10. The opposite end of the winding terminates in a lead-wire 52 which is connected to a terminal strip 53. The latter is secured to the side wall 38 of the box 30 by a screw 54, the said strip being insulated from the box and from the screw by insulating elements 55 and 56. The terminal strip 53 is connected by a wire 57 to one side of a battery 58 (Figure 2), a switch 59 being arranged between 35 the said strip and battery. The opposite side of the battery 58 is connected by a wire 60 to the terminal strip 37. It will be apparent, therefore, that when the switch 59 is closed, a circuit is established through the winding of the electro-magnet 50, the said circuit including the battery 58, wire 60, terminal strip 37, spring 36, latch-piece 29, member 44 to ground, ground to the lead-wire 52, terminal strip 53, wire 57 and switch 45 59. Upon energization of the electro-magnet 50 45 the upper end of the member 44 is pulled toward the pole-piece 47 against the action of the spring 46, thereby moving the shoulder 43 of the member 44 out of the path of the latch-piece and permitting the sash 15 to descend to its closed position. 50

From the foregoing it will be apparent that the device may be operated at will, either at the window with which it is associated or at a remote point, to cause the window with which it is associated to close. Various forms of automatic remote control devices may be employed. For example, the device may be operated at a predetermined time to effect the release of the window, this being of particular advantage when it is employed in connection with a bedroom window. In such a case a shunt around the switch 59 is provided by wires 61 and 62, the said wires being connected to a switch (not shown) which is controlled by the mechanism of a clock 63, the 60 clock controlled switch being of any suitable construction and, as will be obvious, being mounted in the casing of the clock. The clock may be set to close the circuit through the electro-magnet 50 at a predetermined time, for example, at or about the time that the heating system of the 70 building is conditioned to raise the temperature of the room in which the window is located. 65

The invention contemplates the incorporation with the device of a co-operating burglar alarm 75

system. As noted, the latch-piece 29 forms a part of the circuit in which the electro-magnet 50 is included, the said latch-piece electrically connecting the spring 36 and the member 44 when the end 35 thereof is located in one of the notches 28 of the rod 18. However, when the latch-piece 29 is released to permit the window to close it moves to the full-line position shown in Figure 5, thereby permitting the end 42 of the latch-piece to move out of contact with the member 44. The circuit, therefore, through the electro-magnet is broken.

In the embodiment shown in Figure 5 the terminal strip 53 is connected by a wire 64 to a terminal 65 of a switch 66. The latter includes a terminal 67 which is connected by a wire 68 to a battery 69, the opposite side of the battery being connected by a wire 70 to the terminal strip 37. The switch 66 includes a bridge-piece 71 which is rotatable to connect the terminals 65 and 67 whereby to energize the electro-magnet 50 in the manner described. The switch 66 includes a second pair of terminals 72 and 73. The former is connected by a wire 74 to one terminal of a bell 75 or any other suitable type of alarm device, the other terminal of the bell being connected by a wire 76 to the wire 64. The terminal 73 of the switch 76 is connected by the wire 68 to one side of the battery 69. Hence when the bridge-piece 71 is moved to connect the terminals 72 and 73 the bell 75 is connected to one side of the battery.

In the use of the device, assuming the window to be raised, the bridge-piece 71 occupies the horizontal dotted-line position shown in Figure 5. When it is desired to close the window the bridge-piece 71 is moved to the position in which it connects the terminals 72 and 73. During movement of the bridge-piece to this position the terminals 65 and 67 are temporarily connected. The electro-magnet 50 is, therefore, energized during the initial part of the movement of the bridge-piece and the rod 18 is released to permit the window to close. Thus when the window is closed the terminals 72 and 73 of the switch 66 are connected by the bridge-piece. The bell 75, however, is not connected to power at this time as the end 42 of the latch-piece 29 is out of contact with the member 44 (see Figure 5). If, when the switch is conditioned in the manner described, the window is elevated the rod 18 moves upwardly until the end 35 of the latch-piece enters one of the notches 28. As this takes place the latch-piece moves toward a horizontal position, the end 42 thereof moving into contacting relation with the member 44. When the latch-piece contacts with the member 44 a circuit is completed through the bell 75 and the latter, therefore, is energized to sound an alarm. It will be apparent that as the electro-magnet 50 is included in the alarm circuit the member 44 will be moved to break the circuit if the amount of current required by the bell 75 is large enough. In this event, however, as soon as the circuit through the electro-magnet is broken and the member 44 again moves into contact with the latch-piece 29 the alarm is again sounded. This movement of the arm 44 is rapid and hence the bell 75 will give what is in effect a continuous signal. It will be noted that the entry of the end 35 of the latch-piece into a notch 28 permits the latch-piece to pivot upon the pin 30 to the dotted-line position shown in Figure 5, the end 42 of the latch-piece contacting with the member 44 during this movement to, and while it re-

mains in, the position shown. When it is desired only to close the window this may be accomplished by rotating the bridge-piece just far enough to connect the contacts 65 and 67.

In the embodiment shown in Figure 1 a plurality of the control devices are connected in a system which includes a switch 78, a bell 79 and a battery 80, the said switch and bell being similar to and functioning in substantially the same manner as the corresponding parts shown in Figure 5. In this embodiment all of the windows with which the devices are associated may be closed simultaneously by the switch 78, it being understood that any one of the said windows may be closed independently by depressing the operating element 48 of the device which is associated with the window. The switch 78 may, if desired, be conditioned in the manner described in connection with Figure 5 whereby an alarm will be sounded in the event that any one of the various windows is raised. From the foregoing it will be apparent that the device may be associated with various windows of a building, the devices being connected in a system whereby all of the windows may be lowered simultaneously, if desired.

I claim as my invention:

1. In a device of the character described, the combination with a member for holding a window in an open position, of means for moving said member to release said window and permit it to close by gravity, an electric signal and circuit means including a source of electric power and said member, whereby in the event that said window is raised said signal is connected to power.

2. In a device of the character described, the combination with a member for holding a window in an open position, of means including an electric circuit for moving said member to release said window and permit it to close by gravity, said circuit including said member.

3. In a device of the character described, the combination with a member for holding a window in an open position, of circuit means for moving said member to release said window and permit it to close by gravity, an electric signal and auxiliary circuit means including a source of electric power whereby in the event that said window is raised said signal is connected to power, both of said circuit means including said member.

4. In a device of the character described, the combination with a rod which is adapted to be connected to a window, of means for engaging said rod to hold said window in an open position, said means including a latch-piece which is movable under the weight of said window to release said rod, a member for locking said rod and latch-piece against movement, circuit means including a source of electric power for moving said member to release said latch-piece and permit said window to close by gravity, an electric signal and auxiliary circuit means for connecting said signal to power in the event that said window is raised, both of said circuit means including said member and said latch-piece.

5. In a device of the character described, the combination with a rod which is adapted to be connected to a window, said rod being provided with a series of shoulders, of means for engaging any one of said shoulders to hold said window in an open position, said means including a latch-piece which is movable under the weight of said window to permit downward movement of said rod, a member for holding said latch-piece in co-operating relation with any one of said shoulders,

circuit means including a source of electric power for moving said member to release said latch-piece and permit said window to close by gravity, an electric signal and auxiliary circuit means for connecting said signal to power in the event that said window is raised, both of said circuit means including said member and said latch-piece.

6. In a device of the character described, the combination with a rod which is adapted to be connected to a window, of a housing in which said rod is slidably mounted, said housing being adapted to be connected to the frame of said window and including a box and a tubular member, means located in said box for engaging said rod to hold said window in an open position, said means including a latch-piece, an element for locking said latch-piece and rod against movement, circuit means including a source of electric power for moving said element to release said latch-piece and permit said window to lower by gravity, a piston carried by said rod and movable in said tubular member to retard the movement of said window toward its closed position, said circuit means including an electro-magnet, an electric signal and auxiliary circuit means for connecting said signal to power in the event that said window is raised, both of said circuit means including said latch-piece and element.

7. In a device of the character described, the combination with a window and an element which is movable to a position in which it is adapted to hold said window open, of a movable member for locking said element in said position, resilient means for normally holding said member in its locking position, a solenoid, an electric circuit for energizing said solenoid, said solenoid moving said member when energized to release said element and permit said window to close, an electric signal device, a normally open auxiliary electric circuit which includes said device and means for closing said auxiliary circuit when said window is raised, said auxiliary circuit including said element and said member.

8. In a device of the character described, the combination with a window and an element which is movable to a position in which it is adapted to hold said window open, of a movable member for locking said element in said position, resilient means for normally holding said member in its locking position, a solenoid and an electric circuit for energizing said solenoid, said solenoid moving said member when energized to release said element and permit said window to close, said circuit including said element and said member.

9. In a device of the character described, the combination with a window and an element which is movable to a position in which it is adapted to hold said window open, of a movable member for locking said element in said position, resilient means for normally holding said member in its locking position, a solenoid, an electric circuit for energizing said solenoid, said circuit including said movable member, said solenoid moving said member when energized against the action of said resilient means to release said element and permit said window to close, a signal device and an auxiliary electric circuit which is normally open and which includes said device, said element being movable in the event that said window is raised to close said auxiliary circuit.

10. In a device of the character described, the combination with a window and an element which is movable to a position in which it is adapted to hold said window open, of a movable member for locking said element in said position, resilient means for normally holding said member in its locking position, a solenoid and an electric circuit for energizing said solenoid, said circuit including said element, said solenoid moving said member when energized against the action of said resilient means to release said element and permit said window to close, said element breaking said circuit as it moves out of contact with said member.

11. In a device of the character described, the combination with a window and an element which is movable to a position for holding said window open, of a movable member for locking said element in said position, resilient means for normally holding said member in its locking position, a solenoid, an electric circuit for energizing said solenoid, said solenoid moving said member when energized against the action of said resilient means to release said element and permit said window to close, a signal device and an auxiliary electric circuit which includes said signal device, said element, said member and said solenoid, said element being movable to a position out of contact with said member as said window closes thereby maintaining said auxiliary circuit open, said element being movable in the event that said window is raised to contact said member and close said auxiliary circuit, said solenoid upon such occurrence causing said member to vibrate similarly to the armature of a buzzer, thereby to cause said signal device to give a substantially continuous indication.

ROBERT H. BUTTERS.
